SPOOL SUPPLY APPARATUS FOR TEXTILE MACHINES

Stefan Fürst, M. Gladbach, Rhineland, Germany, assignor to Walter Reiners, Waldniel, Lower Rhine, Germany

Application February 4, 1953, Serial No. 334,997

Claims priority, application Germany February 6, 1952

9 Claims. (Cl. 242—35.6)

The present invention relates to textile machines.

More particularly, the present invention relates to an apparatus for supplying spools successively to a predetermined operating station of a textile machine after a spool at the operating station becomes exhausted.

In certain types of textile machines it is the usual practice to hold a plurality of fresh reserve spools of yarn in a container to be successively conveyed therefrom to an operating station each time a spool at the operating station becomes exhausted. Lengths of yarn extend from each of the reserve spools to a clamping or holding means such as, for example, a suction nozzle, and great difficulties arise when a machine of this type handles spools from which the yarn cannot unwind during movement of the spool from the container to the operating station. The reason for this is that the yarn which cannot unwind from the spool becomes stretched and frequently breaks or causes improper movement of the spool during conveying of the latter to the operating station.

One of the objects of this invention is to overcome this disadvantage by providing a machine which is capable of handling spools from which the yarn cannot unwind during movement of the spool to its operating station without any danger of excessive tensioning of a length of yarn extending from the spool and held by a clamping or holding means of the above type.

A further object of the present invention is to provide an apparatus where the part of a spool, from which a length of yarn extends to a holding means, is located at a substantially unchanging distance from the holding means during movement of the spool from a reserve container therefor to a carrier at the operating station of the machine.

With the above objects in view the present invention mainly consists of an apparatus for supplying spools of yarn or the like successively to a predetermined operating station after a spool at the operating station becomes exhausted, this apparatus including a support means and a holding means mounted on the support means for holding an end portion of a length of yarn extending from a spool. A container means is mounted on the support means for holding a plurality of fresh spools in reserve with a part of each spool, from which a length of yarn extends to said holding means, located substantially at a predetermined distance from the holding means. A carrier means is mounted on the support means for carrying a spool at the predetermined operating station with the part of the spool, from which a length of yarn extends to the holding means, also located substantially at the predetermined distance from the holding means. A conveyer means is provided to convey a spool from the container means to the carrier means along a path located substantially at the predetermined distance from the holding means so that a length of yarn extending from a spool to the holding means will not be stretched or slackened appreciably during movement of the spool from the container means to the carrier means.

2

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

Referring now to the drawing which schematically illustrates only a sufficient amount of the structure of a textile machine to afford a full understanding of the invention, it will be seen that a container means 1 is provided on a support means of the machine, and a plurality of fresh spools of yarn 2 are located next to each other in the container means 1 with lengths of yarn 3 respectively extending from each spool 2 to a holding means 4, such as a suction nozzle or clamping device, which is also mounted on the support means of the machine, these lengths of yarn 3 extending through a space located at the front of the container means 1 which is in the form of a substantially U-shaped trough which is downwardly inclined with the top end of the trough shown in the drawing located to the rear of the bottom end thereof.

A release means is provided to successively release the spools 2 from the container means 1, this release means including a substantially U-shaped catch member 5 turnably mounted on the support means of the machine at 6 and being adapted to extend through a cutout formed in the left side of the trough-shaped container means 1, as viewed in the drawing. A bar 7 is fixed to and extends from the member 5 for movement therewith about the pivot 6, and the bar 7 is linked to a rod 8 which is in turn linked to a two-arm lever 10, 11 turnably mounted on the support means of the machine at 9.

When the lever 10, 11 is turned in a clockwise direction, as viewed in the drawing, about the pivot 9, the rod 8 will rise to turn the member 5 also in a clockwise direction about the pivot 6, so that the top arm of catch member 5 will enter the container means 1 to hold all except the bottommost spool 2 in the container means while this bottommost spool 2 is released from the container means 1. Upon return of the parts 5—11 to the position shown in the drawing, the catch member 5 holds all of the spools in the container means, as shown in the drawing, these spools advancing to the position shown in the drawing by gravity.

The thus-released bottommost spool 2 falls onto the inclined chute 12 which is mounted on the support means of the machine and forms a conveying means for conveying the spool, which descends along chute 12 by gravity, to the operating station of the machine where the spool is carried by a carrier means in the form of a two-arm lever 14, 15 turnably mounted on the pivot 13 carried by the support means of the machine. A spool 2' is shown in the drawing at this operating station with the arm 14 extending into the central hollow part of the spool 2'. When a spool 2' becomes exhausted, the tubular support thereof is expelled from the arm 14 by a known means not forming part of the present invention and not shown in the drawing, and the lever 14, 15 is turned, by a means also forming no part of the present invention and not shown in the drawing, to a spool receiving position, shown in dot-dash lines, where the arms 14 and 15 are respectively indicated at 14' and 15'.

After a fresh spool 2' slides down the chute 12 to automatically be located on the arm 14 while the latter is located at 14', the carrier means 14, 15 is returned to the operating position shown in solid lines where the spool 2' is at the operating station with the length of yarn 3' extending from the spool to the holding means 4 about a guide member 22 carried by the support means of the

machine. A link 16 interconnects the arms 15 and 11 so that the release means for releasing the bottommost spool in the container means 1 is automatically operated by movement of the carrier means 14, 15 to and from the spool receiving position.

The yarn lengths 3 extending from the spools 2 in container means 1 to the holding means 4 have a length substantially equal to that indicated by the dimension line 19. The yarn length 3' has a length equal to the length of dimension line 20 plus dimension line 21, and the line 19 is approximately equal to the length of line 20 plus the length of line 21. Furthermore, during movement of each spool from the container means 1 to the carrier means 14, 15, the spool moves through a substantially circular arc whose center is at the holding means 4 so that as each spool moves downwardly along the chute 12 the yarn lengths 3 do not appreciably stretch or slacken.

Therefore, with the apparatus of the invention each time a spool 2' becomes exhausted it is removed from the carrier means 14, 15, and the latter is turned to the spool receiving position shown in dot-dash lines to receive a fresh spool moving down the chute 12, the movement of the carrier means 14, 15 automatically releasing a fresh spool from the container means 1. It will be seen that the container means 1 is located at substantially the same elevation as the holding means 4 while the carrier means 14, 15 is located substantially beneath the holding means 4, and all of these parts of the structure together with the conveying means formed by chute 12 are arranged with respect to each other in such a way that the length of yarn extending from each spool to the holding means 4 does not become appreciably tensioned or slackened during movement of the spool from the container means 1 to the operating station, so that even though the spools are of the type from which the yarn cannot be immediately unwound and even though the yarn lengths 3 cannot be drawn from the holding means 4, there is no danger that the yarn will break even if it is a relatively slender, delicate yarn and, moreover, there is no danger that the spools will fail to move along the desired path to the operating station.

It will be understood that each of the elements described above, or two or more together, may also find a useful application in other types of spool supply apparatus for textile machines differing from the types described above.

While the invention has been illustrated and described as embodied in apparatus for supplying spools in textile machines without excessively tensioning a yarn length extending from each spool, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means for holding a plurality of fresh spools in reserve with a part of each spool, from which a length of yarn extends to said holding means, located substantially at a predetermined distance

from said holding means; carrier means mounted on said support means for carrying a spool at the predetermined operating station with the part of the spool from which a length of yarn extends to said holding means also located substantially at said predetermined distance from said holding means; and conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means.

2. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means for holding a plurality of fresh spools in reserve with a part of each spool, from which a length of yarn extends to said holding means, located substantially at a predetermined distance from said holding means; and carrier means mounted on said support means for carrying a spool at the predetermined operating station with the part of the spool from which a length of yarn extends to said holding means also located substantially at said predetermined distance from said holding means.

3. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means at substantially the same elevation as said holding means for holding a plurality of fresh spools in reserve with a part of each spool, from which a length of yarn extends to said holding means, located substantially at a predetermined distance from said holding means; and carrier means mounted on said support means beneath the level of said holding means and container means for carrying a spool at the predetermined operating station with the part of the spool from which a length of yarn extends to said holding means also located substantially at said predetermined distance from said holding means; and conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means.

4. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means at substantially the same elevation as said holding means for holding a plurality of fresh spools in reserve with a part of each spool, from which a length of yarn extends to said holding means, located substantially at a predetermined distance from said holding means; and carrier means mounted on said support means beneath the level of said holding means and container means for carrying a spool at the predetermined operating station with the part of the spool from which a length of yarn extends to said holding means also located substantially at said predetermined distance from said holding means; and conveying means for conveying a spool from said container means to said carrier means along a path located substantially at said predetermined distance from said holding means so that

a length of yarn extending from a spool to said holding means will not be stretched or slackened appreciably during movement of the spool from said container means to said carrier means, said conveying means comprising a chute mounted on said support and extending downwardly from said container means to said carrier means.

5. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means at substantially the same elevation as said holding means for holding a plurality of fresh spools in reserve with a part of each spool, from which a length of yarn extends to said holding means, located substantially at a predetermined distance from said holding means; carrier means mounted on said support means substantially beneath said holding means for carrying a spool at the predetermined operating station with the part of the spool from which a length of yarn extends to said holding means also located substantially at said predetermined distance from said holding means; and conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means, said conveying means comprising a chute mounted on said support and extending downwardly from said container means to said carrier means.

6. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means at substantially the same elevation as said holding means for holding a plurality of fresh spools in reserve with a part of each spool, from which a length of yarn extends to said holding means, located substantially at a predetermined distance from said holding means; carrier means mounted on said support means substantially beneath said holding means for carrying a spool at the predetermined operating station with the part of the spool from which a length of yarn extends to said holding means also located substantially at said predetermined distance from said holding means; conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means, said conveying means comprising a chute mounted on said support and extending downwardly from said container means to said carrier means; and release means operatively connected to said container means for releasing a spool therefrom for movement to said carrier means after a spool at the latter becomes exhausted.

7. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means at substantially the same elevation as said holding means for holding a plurality of fresh spools in reserve with a part of each spool, from which a length of yarn extends to said holding means, located substantially at a predetermined distance from said holding means; carrier means mounted on

said support means substantially beneath said holding means for carrying a spool at the predetermined operating station with the part of the spool from which a length of yarn extends to said holding means also located substantially at said predetermined distance from said holding means, said carrier means being movable to and from a spool receiving position; conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means, said conveying means comprising a chute mounted on said support and extending downwardly from said container means to said carrier means; and release means operatively connected to said container means for releasing a spool therefrom for movement to said carrier means after a spool at the latter becomes exhausted, said release means being operatively connected to said carrier means to be operated thereby upon movement of said carrier means to and from said spool receiving position.

8. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means and having one side adjacent said holding means and an opposite side distant from said holding means and located therefrom by a distance of predetermined magnitude, said container means being adapted to hold a plurality of fresh spools in reserve with a part of each spool, from which a length of yarn extends to said holding means, located at said opposite side of said container means; carrier means mounted on said support means beneath the level of said holding means and container means for carrying a spool at the predetermined operating station with the part of the spool from which a length of yarn extends to said holding means also located substantially at said predetermined distance from said holding means; and conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means.

9. Apparatus for supplying spools of yarn and the like successively to a predetermined operating station after a spool at the operating station becomes exhausted, comprising, in combination, support means; holding means mounted on said support means for holding an end portion of a length of yarn extending from a spool; container means mounted on said support means with one end of said container means located above an opposite end thereof, said container means being laterally spaced from said holding means with one side of said container means located adjacent said holding means and an opposite side of said container means spaced from said holding means by a predetermined distance greater than the distance between said holding means and said one side of said container means, the latter being adapted to hold a plurality of substantially horizontally extending fresh spools in reserve with a part of each spool, from which a length of yarn extends to said holding means, located at said opposite side of said container means; carrier means mounted on said support means substantially beneath said holding means for carrying a spool at the predetermined operating station with the part of the spool from which a length of yarn extends to said holding means also located substantially at said predetermined distance from said holding means.

ing means; and conveying means for conveying a spool from said container means to said carrier means along a path located substantially at said predetermined distance from said holding means so that a length of yarn extending from a spool to said holding means will not be stretched or slackened appreciably during movement of the spool from said container means to said carrier means.
